[57] **CLAIM**

The ornamental design for a playground dragon head, as shown and described.

DESCRIPTION

FIG. 1 is a perspective view of the playground dragon head design; the broken line showing the slide is for illustrative purposes only and forms no part of the claimed design; FIG. 2 is a front plan view of the playground dragon head design of the subject invention of FIG. 1;

FIG. 3 is a left side view of the playground dragon head design of FIG. 1, the opposite side being a mirror image thereof;

FIG. 4 is a rear plan view of the playground dragon head design of FIG. 1;

FIG. 5 is a top plan view of the playground dragon head design of FIG. 1; and,

FIG. 6 is a bottom plan view of the playground dragon head design of FIG. 1.
